REAR-STRIKE TYPEWRITER MECHANISM

Harry Johnson, Elizabeth, N. J., assignor to
 Ralph C. Coxhead Corporation, Newark, N. J.,
 a corporation of Delaware

Application November 21, 1951, Serial No. 257,587

18 Claims. (Cl. 197—6.5)

1

This invention relates to typewriters and, more particularly, to a typewriter for typing on certain materials that cannot be satisfactorily typed on with a conventional typewriter.

Certain nonabsorbent substances, including plastics, cannot be typed on with the ordinary typewriter because of the need for penetration of the ink, at least to some extent, into the surface. It has been found that plastics can be typed on by heating the type and using a thermoplastic or thermosensitive type ribbon. Such a typewriter is shown in Resch Patent 2,515,881, and the typewriter of the present invention is in certain respects an improvement over the typewriter there shown. This typewriter is particularly useful for typing code designations on lengths of flexible plastic tubing which may subsequently be severed into short lengths for slipping over the ends of electrical wiring to designate the identity of the wire.

The improvements of the present invention are incorporated in a rear-strike typewriter of the sort known in the trade as the "Vari-typewriter" in which type is embossed upon a type shuttle slidably mounted on a cylindrical anvil positioned in front of the article to be typed on, the shuttle being movable along the anvil responsive to operation of the type keys to index any desired character at the printing point, a hammer behind the anvil striking the object and driving it against the type shuttle and a type ribbon interposed between the object and the shuttle to form the type impression.

In the form shown of the present invention, an improved heating unit is mounted on top of the anvil and heats the anvil which in turn heats the shuttle. The type ribbon is thermosensitive type ribbon in which the pigment is softened by heat to form the printed impression. Instead of the usual spring-driven hammer, the hammer action is a combination of an initial hammer blow plus a steady hammer pressure so as to form a clear type impression.

The typewriter of the present invention is particularly suited for typing on plastic tubing and to that end incorporates an improved guide for accommodating plastic tubing of various sizes.

Among the objects of the present invention are to provide a typewriter that will type more clearly and uniformly on smooth, nonabsorbent substances, including plastics; to provide such a typewriter in which the type impression is uniform and produced by the combination of an initial blow plus a steady pressure; to provide such a typewriter of simple, dependable con-

2

struction; to provide an improved typewriter for typing on small-diameter, flexible tubing; and to generally improve typewriters of the class described.

5 Other objects and objects relating to details and economies of construction will be more readily apparent from the detailed description to follow.

My invention is clearly defined in the appended 10 claims. In the claims, as well as in the description, parts are at times identified by specific names for clarity and convenience, but such nomenclature is to be understood as having the broadest meaning consistent with the context 15 and with the concept of my invention as distinguished from the pertinent prior art. The best form in which I have contemplated applying my invention is illustrated in the accompanying drawings forming part of this specification, in 20 which:

Fig. 1 is a somewhat diagrammatic fragmentary top plan view of a typewriter according to the present invention, the forward portion of the typewriter, including the forward portions of 25 the key levers and associated mechanism, being omitted.

Fig. 2 is a somewhat diagrammatic vertical section of the typewriter taken generally on the line 2—2 of Fig. 1, portions of the mechanism 30 being omitted for clarity and convenience of illustration.

Fig. 3 is an enlarged vertical section of the anvil, shuttle, and heating unit taken through the printing point and showing the relationship 35 of these parts with the tube guide and hammer.

Fig. 4 is a somewhat diagrammatic illustration of a section of flexible "Vinylite" tubing of the sort which the present machine is adapted to type on.

Fig. 5 is a schematic wiring diagram of the 40 electrical system employed in the typewriter.

The present invention will be described as applied to a typewriter of the type known in the trade as the "Vari-typewriter," although the invention in certain of its broader aspects is capable 45 with some modification of being applied equally well to other kinds of typewriters.

The typewriter shown and described has been 50 designed particularly for permanent typing upon flexible, small-diameter, "Vinylite" tubing of the type commonly used as terminal insulation for wiring. It is desirable to have the terminal insulation of complicated electrical wiring so marked that the individual wires may be identified readily 55 at any later date. Accordingly, by typing appro-

priate characters on "Vinylite" tubing and subsequently cutting the tubing into short lengths positionable at terminal endings of wiring, a permanent, positive means of identifying the wiring is provided. Such a specimen of tubing is shown in Fig. 4 of the drawings. Of course, a typewriter embodying features of the present invention is capable of a multiplicity of other uses as well as typing on such tubing.

The typewriter shown in part in Fig. 1 is in general organization similar to the commercial "Vari-typewriter" typewriter and is generally similar to the typewriter described in Trego Patent 1,967,273. This typewriter has a carriage 10 which is mounted on a guide 13 for movement past a printing point 11. The carriage 10 is generally similar to the carriage of Resch Patent 2,515,381 and is provided with a clamp 12 at each end of the carriage for receiving a length of tubing 14 to be typed on.

Movement of the carriage 10 past the printing point is controlled by an escapement mechanism 18. The carriage escapement mechanism may be generally similar to that shown in Trego Patent 1,965,677 and provides a uniform carriage escapement movement for all characters of the alphabet. A cylindrical anvil 15 is mounted just in front of the printing point 11. An arcuate type shuttle 16 conforming to the curvature of the anvil is slidably mounted for circumferential movement about the anvil to index any desired type character at the printing point 11. Preferably, the type shuttle, which is of the usual kind used in the "Vari-typewriter," has three lines of embossed type characters thereon, the anvil and shuttle being raised by operation of the Cap and Fig. shift keys, but the anvil being otherwise fixed.

A hammer 17 is mounted on a horizontal pivot 19 under the carriage and extends in a generally semicircular form to the rear of the carriage, terminating in a head or impression-forming portion 20 located behind the tubing 14 at the printing point. The hammer is spring operated in its printing stroke, being driven forward against the tubing by a hammer spring 23 to form each printed impression. A helical spring 27 carried on a hammer check rod 29 depending from the lower rear portion of the hammer 17 checks forward movement of the hammer and provides a hammer stroke of the desired characteristics for ordinary typing. The hammer 17 is returned by an escapement mechanism powered by a spring motor 21 mounted on the back of the typewriter and intermittently rewound by an intermittently operated electric motor 22. The escapement mechanism 18 controls operation of the hammer 17 as well as spacing movement of the carriage 10 as shown in Trego Patent 1,965,677 in order to properly correlate hammer movement and carriage spacing.

Operation of the hammer 17 is initiated by raising the forward portion of the trip frame 24 (Fig. 2). The trip frame 24 comprises a bail which extends above the rear end of each of the printing keys. The trip frame is operated upon actuation of any of the printing keys and also upon actuation of the space bar, in order to operate the carriage escapement mechanism 18 and cause spacing movement of the carriage. Accordingly, upon actuation of the space bar, the rear end of the space bar lever 25, which is generally similar to the rear ends of the printing key levers, raises the trip frame 24 also in producing carriage spacing, thus initiating actuation

of the hammer. However, upon operation of the space bar, a space bar hook (not shown) is interposed in the path of the hammer 17 to check or arrest forward or counterclockwise movement of the hammer short of a complete impression-forming stroke but still allowing sufficient movement of the hammer to actuate the escapement mechanism 18 and produce carriage spacing. This general organization for checking the hammer short of a full stroke upon operation of the space bar is known and does not constitute part of the present invention.

A type ribbon 30 is interposed between the tubing 14 and the type shuttle 16 at the printing point, this type ribbon being fed from left to right in the customary manner as indicated in Fig. 1. The type ribbon 30 is a single-use, thermosensitive type ribbon, known in the trade as branding tape, which is capable of forming type impressions when the ribbon or the type is heated to an elevated temperature so as to soften the ribbon pigment for the printing operation. This ribbon is fed from a relatively large reel 31 mounted on the left side of the typewriter and is progressed by feed rolls 32 at the right side of the typewriter (see Fig. 1), the ribbon being discarded after one use.

According to the present invention, the anvil 15 is heated to an elevated temperature by a heating unit mounted on top of the anvil and comprising a circular, metallic cap 34 of the approximate diameter of the anvil and having a depending skirt in thermal contact with the top edge of the anvil throughout its circumference. The cap 34 is heated to elevated temperature by an electrical resistance heating element 36 contained within the cap, the heat of the cap being transmitted to the anvil and in turn to the shuttle 16. The shuttle is maintained at a more or less constant temperature of about 200° F., the organization being such that, after the shuttle has been raised to operating temperature, the heat losses from the anvil, shuttle, and cap are approximately equal to the heat input; and, therefore, a thermostat or other heat control to prevent overheating of the anvil and shuttle is not required.

In printing with a thermosensitive ribbon such as the ribbon 30, it is desirable to have an initial impact between the type and the work, together with a steady pressure for an appreciable period of time to soften the ribbon pigment and form the impression. Accordingly, in a typewriter of the present invention, a solenoid-operated mechanism is provided to increase and maintain for a period the hammer pressure against the work when forming the printed impression. This mechanism comprises an electrical solenoid 37 mounted on the typewriter frame, the solenoid drawing an iron core 38 downwardly to operate a bell crank lever 39, which is mounted for rotation about a fixed pivot 40, one end of the bell crank lever being connected with the core 38 by a link 41. A roller 42 is mounted on the other end of the bell crank lever 39 and, upon actuation of the solenoid 37, engages against and presses forwardly upon the rear edge of the hammer 17 so as to press forwardly on the hammer and provide a steady and continuous forward pressure of the hammer against the tubing 14 so long as the solenoid is actuated.

The electric circuit of the typewriter is indicated in the wiring diagram of Fig. 5. The motor 22 is energized to wind the spring motor 21 whenever the spring motor becomes unwound, a switch 75 43 being closed by unwinding of the motor 21

to cause operation of the motor 22 and being opened upon the spring motor again being wound. A filter 48 may be inserted in the line if desired in order to prevent electrical interference if the typewriter is to be operated on shipboard. This portion of the wiring is generally old and has been used in the Vari-typer for a number of years.

The circuit to the heating unit, including the heating element 36 and the solenoid 37, is controlled by a manually operated electric switch 44 which may be a toggle switch mounted on the forward portion of the typewriter frame. Closing of this switch energizes the heating unit 36 and the circuit to the solenoid 37, which is connected in parallel with the heating unit 36 and controlled by three switches connected in series, all of which may be of the microswitch type. The first of these switches is a hammer-operated switch 45, which is normally open but which is moved to closed position by a projection 46 mounted on the lower end of the hammer check rod 29, this switch being closed as the hammer approaches forward or impression-forming position and being reopened as the hammer moves rearwardly from extreme forward position. This switch causes the solenoid 37 to be energized so as to furnish the proper hammer pressure for forming the printed impression, as above described.

A second or trip-frame-operated switch 47, in series with the hammer-operated switch 45 and also normally open, is operated by link 48 to close the switch upon the trip frame being raised by operation of any printing key or the space bar 25 and remains closed until the printing key or space bar is released, so as to permit the hammer 17 to return to normal position. Closing of the trip frame switch 47 occurs before release of the hammer 17 for its printing stroke and before closing of the hammer-operated switch 45; and, therefore, the solenoid 37 is energized upon closing of the hammer-operated switch. However, the hammer-operated switch 45 remains closed until the hammer commences its return to rearward or normal position, which cannot occur until the solenoid is no longer energized. The circuit through the solenoid 37 is interrupted by opening of the trip-frame-operated switch 47, which occurs when the printing key is released, and the trip frame drops to normal position. Accordingly, the solenoid 37 is energized by closing of the hammer-operated switch 45, and the circuit through the solenoid is interrupted upon opening of the trip-frame-operated switch 47.

A space-bar-operated switch 49, which is normally closed, is also in series with the switches 45 and 47. This switch which is operated by a link 53 connected to the space bar lever 25 is opened upon operation of the space bar to raise the trip frame 24 and remains open until the space bar is released and the space bar lever 25 returns to normal position. Accordingly, upon operation of the space bar, the space-bar-operated switch 49 is open while the trip-frame-operated switch 47 is closed and vice versa, and thereby energization of the solenoid 37 is prevented as the hammer 17 moves forward in its curtailed stroke during operation of the space bar in order to operate the escapement mechanism for carriage spacing.

Summarizing the operation of the portion of the electrical system particularly concerned with the typing with a heat-sensitive ribbon, the heating unit 36 is continuously energized so as to heat

the anvil 15 and type shuttle 16 to the desired temperature. Upon striking a printing key, the trip-frame-operated switch 47 is closed as the trip frame is raised to release the hammer 17. Forward movement of the hammer causes the hammer-operated switch 45 to close, the trip-frame-operated switch 47 and the space-bar-operated switch 49 remaining closed, so as to energize the solenoid 37 and furnish a constant continuous pressure as long as the key is held down so as to properly form a printed impression. Then, when the printing key is released, the trip frame 24 drops, opening the circuit through the solenoid 37 and permitting the hammer to return to rearward normal position. Upon operation of the space bar, the space-bar-operated switch 49 is opened so as to prevent energization of the solenoid 37, even though both of the switches 45 and 47 are closed.

A pair of guides 50 and 51 are mounted on the typewriter frame at the left and right-hand sides, respectively, of the printing point for supporting the tubing 14 against sagging. These guides have an upwardly opening, generally U-shaped contour as indicated in Fig. 3 for receiving and supporting the tubing. The interior contour of each of the guides is generally circular except for a converging, forwardly extending guide portion or notch 52 for vertically aligning the tubing with the topmost line of embossed type on the shuttle, this line of type being operative when the shift keys are not operated. The guides 50 and 51 provide for aligning tubing of various diameters with the shuttle 16 so as to form clear type impressions on the tubing.

I claim:

1. In a rear-strike typewriter, embossed type, a pivotally mounted hammer, a hammer spring biasing the hammer forwardly for a printing stroke to drive work to be typed on against the type, an escapement mechanism for controlling operation of the hammer, and mechanism, including an electrical solenoid energized upon forward movement of the hammer in its printing stroke, for maintaining an increased pressure of the hammer against work to be typed on during formation of a type impression.

2. In a rear-strike typewriter for printing with the aid of heat, a heated type shuttle having type symbols embossed thereon and movable to index selected symbols at a printing point, a movable carriage for supporting work to be typed on, a thermosensitive type ribbon interposed between the work and the shuttle, a hammer in rear of the shuttle for driving the work against the type ribbon and shuttle to form a type impression, a spring for driving the hammer forwardly against the work in its printing stroke, and mechanism, including an electrical solenoid operated as the hammer approaches the work, for increasing and maintaining pressure of the hammer against the work during formation of the type impression.

3. In a rear-strike typewriter having a movable carriage for holding work to be typed on, printing keys, embossed type indexed at the printing point in response to operation of the printing keys, a type ribbon, a pivotally mounted hammer for driving the work against the type and ribbon, means biasing the hammer forwardly for a printing stroke, an escapement mechanism for controlling operation of the hammer, and a trip frame moved from normal position by operation of any of said printing keys to operate the escapement mechanism, electrical means oper-

ated upon forward movement of the hammer for maintaining increased pressure of the hammer against the work during formation of the type impression, and means operated by return of the trip frame to normal position for interrupting the circuit to said electrical means upon release of a printing key whereby rearward oscillation of the hammer is permitted.

4. In a rear-strike typewriter having a movable carriage for holding work to be typed on, printing keys, embossed type indexed at the printing point in response to operation of the printing keys, a type ribbon and a pivotally mounted hammer for driving the work against the type and ribbon; means for driving the hammer forwardly against the work for a printing stroke, electrical means operated upon forward movement of the hammer for pressing forwardly on the hammer during formation of the type impression, and means operatively connected with the printing keys for interrupting the circuit to said electrical means upon release of a printing key, whereby rearward oscillation of the hammer is permitted.

5. In a rear-strike typewriter for printing with the aid of heat, a type shuttle having type symbols embossed thereon and movable to index selected symbols at a printing point, a movable carriage for supporting work to be typed on, a thermosensitive type ribbon interposed between the work and the shuttle, a hammer in rear of the shuttle for driving the work against the type ribbon and shuttle to form a printed impression, a spring for driving the hammer forwardly against the work in its printing stroke, and mechanism, including an electrical solenoid operated as the hammer approaches the work, for increasing and maintaining pressure of the hammer against the work during formation of a type impression.

6. In a rear-strike typewriter for printing with the aid of heat, type indexed at a printing point, a movable carriage for supporting work to be typed on, a thermosensitive type ribbon interposed between the work and the shuttle, a hammer in rear of the shuttle for driving the work against the type ribbon and shuttle to form a printed impression, a spring for driving the hammer forwardly against the work in its printing stroke, and mechanism, including an electrical solenoid operated as the hammer approaches the work, for increasing and maintaining pressure of the hammer against the work during formation of the printed impression.

7. In a typewriter for printing with the aid of heat and having a thermosensitive type ribbon, an anvil having a cylindrical outer surface, an arcuate type shuttle having type characters embossed thereon and having an arcuate rear surface mounted for sliding movement along the outer surface of the anvil to index selected type at a printing point, and a cylindrical heating unit mounted above the anvil and comprising a cylindrical, metallic cap having a generally flat, circular portion and having a depending, cylindrical skirt in thermal contact with the anvil throughout its circumference, and an electrical resistance heating coil mounted on the underside of the circular portion for heating the anvil and shuttle.

8. In a typewriter for printing with the aid of heat and having a thermosensitive type ribbon, an anvil having a cylindrical outer surface, an arcuate type shuttle having type characters embossed thereon and having an arcuate rear sur-

face mounted for sliding movement along the outer surface of the anvil to index selected type at a printing point, and a cylindrical heating unit mounted above the anvil and comprising a cylindrical, metallic cap having a generally flat, circular portion and having a depending, cylindrical skirt in thermal contact with the anvil throughout its circumference, and an electrical heating means mounted within the cap for heating the anvil and shuttle.

9. In a rear-strike typewriter having embossed type indexed at a printing point and a type ribbon, a hammer for driving work to be typed on against the type and ribbon and comprising an elongated hammer arm mounted for oscillation on a fixed pivot and a work-engaging head, and hammer-operating means, including a bell crank mounted on a fixed pivot; a roller mounted on the free end of one arm of the bell crank and adapted to engage against the rear of the hammer arm between the hammer arm pivot and the head, and electromagnetic means, including a solenoid and a core linked with the other arm of the bell crank, for oscillating the bell crank about the pivot to press the hammer against the work during formation of a type impression.

10. In a rear-strike typewriter having embossed type indexed at a printing point and a type ribbon, a hammer for driving work to be typed on against the type and ribbon and comprising an elongated hammer arm mounted for oscillation on a fixed pivot and a work-engaging head; and hammer-operating means, including a bell crank mounted on a fixed pivot, one arm of the bell crank being adapted for engagement against the rear of the hammer arm between the pivot and the head, and electromagnetic means connected with the other arm of the bell crank for oscillating the bell crank about the pivot to press the hammer against the work during formation of a type impression.

11. In a rear-strike typewriter, type indexed at a printing point, a pivotally mounted hammer for driving work to be typed on against the type, a hammer spring biasing the hammer forwardly for a printing stroke, an escapement mechanism for controlling operation of the hammer, and electrically operated mechanism including an electrical solenoid energized upon forward movement of the hammer in its printing stroke for maintaining an increased pressure of the hammer against work to be typed on during formation of a type impression.

12. In a rear-strike typewriter, type indexed at a printing point, a pivotally mounted hammer for driving work to be typed on against the type, a hammer spring biasing the hammer forwardly for a printing stroke, an escapement mechanism for controlling operation of the hammer, and mechanism including an electrical solenoid energized upon forward movement of the hammer in its printing stroke for maintaining an increased pressure of the hammer against work to be typed on during formation of a type impression.

13. In a rear-strike typewriter having a movable carriage for holding work to be typed on, printing keys, embossed type indexed at a printing point in response to operation of the printing key, a space bar, a type ribbon, a hammer for driving the work against the type and ribbon, means biasing the hammer forwardly for a printing stroke, an escapement mechanism for controlling operation of the hammer and spac-

ing movement of the carriage, and a trip frame moved from normal position to operate the escapement mechanism by operation of any of the printing keys or the space bar; electrical means for maintaining increased pressure of the hammer against the work during formation of the type impression, an electrical switch actuated by forward movement of the hammer for operating said electrical means, a second electrical switch operated by return of the trip frame to normal position for interrupting the circuit to said electrical means upon release of the printing key whereby rearward oscillation of the hammer is permitted, and a third electrical switch operated by actuation of the space bar for preventing operation of said electrical means upon actuation of the space bar.

14. In a rear-strike typewriter having a movable carriage for holding work to be typed on, printing keys, embossed type indexed at a printing point in response to operation of the printing key, a space bar, a type ribbon, a pivotally mounted hammer for driving the work against the type and ribbon, means biasing the hammer forwardly for a printing stroke, an escapement mechanism for controlling operation of the hammer and spacing movement of the carriage, and a trip frame moved from normal position to operate the escapement mechanism by operation of any of the printing keys or the space bar; electrical means operated upon forward movement of the hammer for maintaining increased pressure of the hammer against the work during formation of the type impression, means operated by return of the trip frame to normal position for interrupting the circuit to said electrical means upon release of the printing key whereby rearward oscillation of the hammer is permitted, and means operated by actuation of the space bar for preventing operation of said electrical means upon actuation of the space bar.

15. In a rear-strike typewriter having a movable carriage for holding work to be typed on, printing keys, embossed type indexed at a printing point in response to operation of the printing keys, a space bar, a type ribbon, a pivotally mounted hammer for driving the work against the type and ribbon, means biasing the hammer forwardly for a printing stroke, an escapement mechanism for controlling operation of the hammer and spacing movement of the carriage, and a trip frame moved from normal position to operate the escapement mechanism by operation of any of the printing keys or the space bar; electrical means for maintaining increased pressure of the hammer against the work during formation of the type impression, and three electrical switches connected in series with said electrical means, one of said switches being normally open

10

and closed by forward movement of the hammer, a second of said switches being normally open and closed by movement of the trip frame from normal position, and a third of said switches being normally closed and opened by actuation of the space bar.

16. In a rear-strike typewriter having a movable carriage for holding work to be typed on, printing keys, embossed type indexed at the printing point in response to operation of the printing keys, a type ribbon and a pivotally mounted hammer for driving the work against the type and ribbon; means for driving the hammer forwardly against the work for a printing stroke, electrical means for pressing forwardly on the hammer during formation of the type impression, an electrical switch in circuit with the electrical means and actuated by forward movement of the hammer for operating said electrical means, and an electrical switch operatively connected with the printing keys for interrupting the circuit to said electrical means upon release of a printing key to permit rearward oscillation of the hammer.

17. In a rear-strike typewriter having movable type indexed at the printing point and a hammer for driving work to be typed on against the type to form a type impression, a guide for supporting flexible tubing of various sizes at the printing point, said guide comprising a substantially flat plate having a generally U-shaped inner contour for receiving the tubing and the forward portion of the inner wall of the guide being notched to form a converging guide portion directed towards the type.

18. In a typewriter for printing with the aid of heat and having a thermosensitive type ribbon, an anvil having a cylindrical outer surface, an arcuate type shuttle having type characters embossed thereon and having an arcuate rear surface mounted for sliding movement along the outer surface of the anvil to index selected type at a printing point, and a heating unit mounted above the anvil and comprising a metallic cap covering the anvil and having a depending circular skirt in thermal contact with the anvil throughout its circumference, and an electrical resistance heating unit mounted adjacent the underside of the metallic cap for heating the cap, anvil, and shuttle.
